UNITED STATES PATENT OFFICE.

JOHN F. APPLEBY, OF SANTA CRUZ, CALIFORNIA, ASSIGNOR TO THE
WILLIAM DEERING & COMPANY, OF CHICAGO, ILLINOIS.

GRAIN-BINDER.

SPECIFICATION forming part of Letters Patent No. 594,842, dated December 7, 1897.

Application filed February 21, 1893. Serial No. 463,284. (No model.)

To all whom it may concern:

Be it known that I, JOHN F. APPLEBY, a citizen of the United States, residing in Santa Cruz, in the county of Santa Cruz and State of California, have invented certain new and useful Improvements in Grain - Binders, of which the following is a description.

This invention relates to that class of binders now in general use in which the grain dis-
10 charged from the harvester onto a binding-table is carried wisp by wisp by packers against a tripping-arm or its equivalent.

My binder is of the kind in which no clutch is used, but instead one having the main gear
15 so mutilated that the driving-pinion passes out of engagement at the end of each revolution, a provision being made so that, near the ending of the rotation that binds a bundle, a spring shall be put in tension in order that
20 its energy may be exerted to give the binder enough of its initial movement, when set free by a tripping-arm or equivalent device that is influenced by the accumulating gavel, to carry the teeth of the mutilated gear into
25 mesh with the constantly-moving driving-pinion and thereby cause it to continue the movement first imparted to the said gear by the spring, the object being to make available a clutching device in such a way that the bind-
30 ing devices are started promptly and with a quick movement—that is, actuate the clutch-
ing device such that as little delay as possible shall exist between the time that the gavel is ready to be bound and the starting
35 of the said binding devices. My construc-
tion overcomes the difficulty that is met with in binding devices having clutches of the ordinary kind in which sometimes as much as a half-revolution of the driving-shaft is made
40 before the said binding devices are started. It is desirable in all binders, particularly in those that move constantly, that after the proper size of the bundle has once been reached the feeding devices should not have
45 an opportunity to bring down still more grain. In the present instance not only the mutilated gear is started suddenly forward, but as the latter is the prime mover of all the parts of the binder that have to do with plac-
50 ing the band and uniting the same it may be

said that the self-binder practically as a whole is given the initial part of the rotation required to bind a succeeding bundle.

In the drawings, Figure 1 is a sectional elevation showing only such parts of a grain-
55 binder of the Appleby type as pertain to my invention. Fig. 2 is a similar view showing several of the parts in their positions after having been given their initial movements. Fig. 3 is a section on the line 3 3 of Fig. 1, 60 and Fig. 4 is a section on the line 4 4 of Fig. 1.

A is the continuously-revolving packer-
shaft actuated by the harvester-gearing and
driving the packers, which may be any of
the well-known kinds. 65

In Fig. 1 is shown a packer B, (of the kind of which two are generally used,) which is hung upon a crank on the packer-shaft and which has its lower end held by a swinging link pivoted to the binder-frame. Geared to
70 the packer-shaft by a pair of bevel-gears, or continuously rotated by any means, is a rapidly-running driving-shaft C, having at its upper end a pinion c.

D is a mutilated bevel-gear secured to the
75 main shaft and thus adapted to drive the band-placing, band-uniting, and bundle-dis-
charging devices and to engage with the continuously-revolving pinion c when set free
and impelled by the power stored for the pur-
pose. 80

The tripping and incidentally the com-
pressor arm F is secured to the rock-shaft F',
which has suitable bearings in the main frame. Preferably cast integral with the gear D is a
85 cam D', which controls the arm F. This it does in such a manner that the arm may per-
form both of its functions, that of a tripping-
arm and a compressor-arm, preferably in the following manner: G is a lever fulcrumed
90 near its middle in the main frame at g and having one end, g', adapted to track upon the cam D' and the other end, g², linked to an arm H on the rock-shaft F' by means of the connect-
ing device I. In order that the cam may
95 control the lever with the least friction and the lever also move the cam with the least resistance, the roller g³ is provided.

The cam D' by the connections above de-
scribed serves to hold the arm F in an erect 100

position during the operation of packing and compressing the grain and at the time immediately following the uniting of the ends of the band allows it to fall out of the way of the 5 bundle as it is being discharged.

The linking device I is made elastic in regard to its length for the usual purpose of preventing undue strain upon the compressing appliances, and, further, its elasticity is utilized by me for forming the storage of energy I desire for giving the wheel D its initial movement when set free by the tripping mechanism. The said linking device I may be constructed in various ways, the most preferable 15 being that shown in the drawings, consisting of the rod I' and the parts shown.

I have thought best to embody the spring above referred to as serving as a reserve power for giving the binder its initial movement in 20 the compressor-spring. Stated shortly, the compressor-spring may be considered and will be considered in some of my claims as having two functions. To accomplish the specific purpose of embodying my said initial-movement spring in that of the compressor, I provide the declivity d' on the cam D and so locate the lever G that, with the binding devices in a position of rest, the spring I³ will be under tension. The spring-rod I' is hooked into an 25 eye in the arm g² of the lever G. In order that the spring may be drawn to a state of tension while passing over the declivity d', a stop, in this instance the part J, soon to be described, is used. To so resist the action of the spring, 30 I provide the detent J. For convenience I give the detent the form of a pawl and pivot it on the pin g and thus make the latter serve not only as a fulcrum of the lever G, but as an axis of movement for the detent. On the 35 periphery of the wheel D is formed a portion of a flange and in it cut the notch J'. In Fig. 2 the detent is shown withdrawn, but it will be readily understood that if the wheel D be turned in the direction indicated by the arrow and the detent be forced upward at the proper interval its end will be thrown into the notch. This notch is so placed relative to the 40 space formed in the mutilated gear that when the pinion is running idly in the latter the 45 detent shall hold the wheel in that position. Connecting the yoke I² of the link with the 50 detent J is the rod J².

Turning to Fig. 1, it will be understood that the spring I³ being drawn into a state of tension by means of the rod I' and the nut i a pressure will be exerted to force I² upward and force the hook portion of the detent J into the notch on the wheel and of course hold it there. Although not necessary it is 55 perhaps proper to mention that while the compressing devices are permitted to drop, because of the cam D' setting the lever G free, the detent in this case is dropped far away from the wheel and is for the time functionless. For the sake of clearness the pinion is 60 omitted from the shaft C in Figs. 1 and 2, but it may be considered as present, as shown in

the remaining figures, and the operation will be clearly understood by paying only a strict regard to Figs. 1 and 2.

Assuming the parts of a binder to be at a state of rest and the spring adapted to exert itself to turn the wheel in a forward direction—as, let us say, in this instance, by a pressure of the roller upon the declivity d'—the 70 tripping-arm F being connected directly to the detent J through the instrumentality of a link or linking device, the movement of the said arm under pressure of the gavel will draw the detent from engagement with the notch J', which done the wheel will be started forward by the resilience of the spring and its teeth forced quickly into engagement with those of the pinion. I make the notch J' of sufficient depth to give an abundance of wear- 85 ing-surface to the working end of the detent, and in order to do so preferably make the notch J' quite deep, so that a considerable movement of the detent will be required to set the binding devices free. The object of so 90 doing will be understood if we suppose that the spring I³, with the parts at rest, is under a certain degree of tension while the grain accumulates against the arm F. Its movement while drawing the detent from engagement 95 will also increase the tension of the spring I³, which increase of tension will find relief only in making still more prompt the initial movement of the wheel D. This desirable result it has seemed to me is most 100 easily reached by making the one spring I³ serve the two purposes above referred to. The binding devices once set in motion will so continue to move until the mutilation in the gear reaches the continuously-rotating 105 pinion. Just previous to such time, however, the cam D' forces the lever G to its place of rest, moving the declivity d' so far that the pressure of the spring will, indirectly, act 110 upon the decline.

In order to sustain the bearing C' for the shaft C at the upper end of the latter, a lug is cast upon the frame. A part, however, of the said lug only is shown and is given the letter M'. This is slotted at M, so as to permit the bearing to move. Resting upon the 115 said bearing is the spring M², suitably secured at one end to any portion of the framework of the machine. N represents the upper surface of the binder-table, over which the grain moves and on which the bundle is formed.

I am aware that it is not new to so provide in a binder that the accumulating grain shall constitute the motive power that moves the binding devices forward.

What I claim as my invention, and desire to secure by Letters Patent, is—

1. In a grain-binder, the combination of constantly-running mechanism, an intermittently-moved driving-wheel, a compressor-cam and a compressor, with locking mechanism unyieldingly connected to said compressor and adapted to be moved thereby in opposition to a spring, elastic mechanism con-

necting said compressor with a lever adapted to be controlled by said cam, the spring of said mechanism acting in opposition to the stress of the bundle upon said compressor to move said locking mechanism and the said lever, substantially as described.

2. In a grain-binder the combination of constantly-running mechanism, an intermittently-moved driving-wheel, a compressor-cam and a compressor with a lever controlled by said cam, a spring-link connecting said lever with said compressor and locking mechanism unyieldingly connected to said compressor and adapted to move in opposition to the stress of said spring-link, substantially as described.

3. In a grain-binder, the combination of the main driving-wheel adapted to be intermittently moved and having a stop on its periphery, a compressor-cam having a declivity, a lever having one end that rests upon the higher part of said declivity when the said driving-wheel is at rest, a compressor-finger, a spring-link connecting said finger to said lever and a detent engaging said stop on said wheel and adapted to be withdrawn therefrom by the pressure of the accumulated gavel, whereby the stress of said spring-link is exerted upon the declivity of said cam to quickly start the said driving-wheel, substantially as described.

4. In a grain-binder, the combination of a constantly-running pinion, a mutilated gear from which all parts of the binding devices receive their movements, a compressor-cam having a declivity, a lever having one end that rests upon the apex of said declivity

when the said driving-wheel is at rest, a compressor-finger, a spring-link connecting the said finger to the said lever and clutching devices engaging said mutilated gear and adapted to be disengaged by the pressure of the accumulated gavel, said clutching devices unyieldingly connected to said compressor, substantially as and for the purpose described.

5. The combination of a constantly-running pinion, a mutilated gear, a cam having a declivity, clutching devices adapted to engage the periphery of said mutilated gear and a trip-finger adapted to disengage said clutching devices, and a lever having one end adapted to rest upon the declivity of said cam and elastically connected to said trip-finger whereby the said gear is given an initial movement when said clutching devices are released, substantially as described.

6. In combination with the continuously-running pinion, the wheel D having the declivity d' and the detent-engaging notch, the lever G, the detent J, the arm F and the elastic linking device I, the latter connected to the said arm G and the detent J so that the stress of the spring of said linking device may be exerted to force the detent into position and to provide the stress necessary to cause the binding devices to be given the initial part of the movement necessary for throwing the clutching devices into engagement, substantially as described.
